UNITED STATES PATENT OFFICE.

ILARION WLAJKO, OF FORBES ROAD, PENNSYLVANIA.

DESIGN FOR A FLY-TRAP.

51,518.

Specification for Design.

Patented Nov. 20, 1917.

Application filed September 21, 1916. Serial No. 121,518. Term of patent 7 years.

To all whom it may concern:

Be it known that I, ILARION WLAJKO, a subject of the Emperor of Austria, residing at Forbes Road, in the county of Westmoreland and State of Pennsylvania, have invented a new, original, and ornamental Design for a Fly-Trap, of which the following is a specification, reference being had to the accompanying drawing, forming part thereof.

Figure 1 is a view in perspective of a fly trap, showing my new design, and,

Copies of this patent may be obtained for five cents each, by addressing the "Commissioner of Patents, Washington, D. C."

Fig. 2 is a central longitudinal sectional view of the same.

I claim:

The ornamental design for a fly trap, as shown.

ILARION WLAJKO.
